DESIGN FOR AN ASHTRAY

Hymen A. Blanchard, Buffalo, N. Y.

Application January 30, 1937, Serial No. 67,352

Term of patent 3½ years

To all whom it may concern:

Be it known that I, Hymen A. Blanchard, a citizen of the United States, residing at Buffalo, in the county of Erie and State of New York, have invented a new, original, and ornamental Design for Ashtrays, of which the following is a specification, reference being had to the accompanying drawing, forming part thereof.

The figure is a perspective view of an ashtray showing my new design.

I claim:

The ornamental design for an ashtray, as shown.

HYMEN A. BLANCHARD,
